DESIGN FOR A BABY CARRIAGE OR SIMILAR ARTICLE

Louis Gottfried, New York, N. Y.

Application November 19, 1941, Serial No. 104,211

Term of patent 7 years

To all whom it may concern:

Be it known that I, Louis Gottfried, without citizenship, residing at 1229 Jerome Avenue, city of New York, in the county of Bronx and State of New York, have invented a new, original, and ornamental Design for a Baby Carriage or Similar Article, of which the following is a specification, reference being had to the accompanying drawing, forming part thereof.

In the drawing

Fig. 1 is a side elevational view of a baby carriage showing my new design; and

Fig. 2 is the bottom plan view thereof.

The characteristic features of my design reside in the portions shown in full lines in the drawing.

I claim:

The ornamental design for a baby carriage or similar article, as shown and described.

LOUIS GOTTFRIED.
